UNITED STATES PATENT OFFICE.

ANATOLE LASMOLES, OF CHATEAUROUX, FRANCE.

ELECTRIC TIME-DETECTOR.

SPECIFICATION forming part of Letters Patent No. 308,416, dated November 25, 1884.

Application filed May 8, 1883. (No model.) Patented in France August 2, 1882, No. 150,429.

To all whom it may concern:

Be it known that I, ANATOLE LASMOLES, a citizen of the French Republic, residing at Chateauroux, in the French Republic, have 5 invented certain new and useful Improvements in Time-Detectors, (for which I have obtained Letters Patent in France, dated August 2, 1882, No. 150,429;) and I do hereby declare the following to be a full, clear, and exact description of the invention, such as will enable others skilled in the art to which it appertains to make and use the same, reference being had to the accompanying drawings, and to the letters marked thereon, which form a part of this 10 specification.

The invention relates to improvements in electric time-detectors; and it consists in the construction, arrangement, combination, and co-operation of a time and detector mechanism, the latter operated electrically, and means for producing the record of the operation of the detector mechanism, substantially as hereinafter described, and shown in the accompanying drawings, in which—

25 Figure 1 is an elevation of part of the detector and time mechanisms, the electrical connections of the former and two stations, and their electrical and recording devices, the face of one of the dials of the station-indicators, as 30 well as the face of the main indicator and the inclosing-casings, being removed. Fig. 2 is a sectional edge view of the time-detector. Fig. 3 is a face view of the dial thereof. Fig. 4 is a like view of part of the mechanism shown in Fig. 1 to more clearly illustrate certain parts thereof. Fig. 5 is a rear face view, the back 35 supporting-plate being removed. Fig. 6 is a side elevation of a portion of the time and detector mechanisms shown in Fig. 2. Figs. 7 and 8 are perspective detail views of parts of the detector mechanism.

The system is composed of any number of stations, two of which are shown in Fig. 1 as an example, and these stations may be located 45 at any desired distance from the main indicator. Each station has an indicator-dial, D', having any desired number of subdivisions, according to the number of records desired to be made in a given time. The dial is loosely 50 mounted on an arbor, a', that carries a ratchet-wheel, r', in rear of the dial and an index-hand, h', in front thereof, both rigidly secured

to the arbor. Each station is also provided with an electro-magnet, M', and the electro-magnets of all the stations are connected with 55 any suitable battery or generator of electricity and with an electro-magnet, M, of the principal detector mechanism. The armatures m' of the station electro-magnets M' carry each a pawl, p', held in engagement with the ratchet 60 r' on arbor a' by an adjusting-screw, s', a pawl, p', holding the ratchet against backward rotation. J' J' are adjusting-screws for regulating the amplitude of the vibration of the armature m'. 65

It is obvious that if the normally-interrupted battery-circuit is closed by any convenient means—as, for instance, the usual circuit-breaker or contact-button, on the depression of which the circuit is closed by a metallic 70 connection—the armature m' will be attracted and the ratchet-wheel rotated the distance of one tooth, and with it the index-hand the distance of one subdivision of the dial, the ratchet having of course a number of teeth equal to 75 the number of subdivisions on the dial. In this manner a record is made at each station whenever the electric circuit is closed. Of course it will be understood that these devices are suitably inclosed in a casing, and that the 80 buttons or other means employed for closing the electric circuit are alone accessible to the person charged with making the records.

The devices just described are in themselves not new, and I do not desire to claim them, 85 except in so far as their combination and co-operation with the mechanisms presently to be described is concerned.

D is the dial of the main indicator, having the usual hour and minute subdivisions and 90 hour and minute hands H H'.

Within the above subdivisions the dial has two annular ridges, d d, over which an annular strip or ring of paper, d', is laid, and stretched thereon by means of the annular stretchers d', 95 as more clearly shown in Fig. 2.

Within the inner annular rib formed by the stretchers d' and the ribs d of the dial D is formed a second dial, D', subdivided into any number of subdivisions. In practice these 100 subdivisions equal in number the total number of subdivisions of the dials D' of all the stations; hence if four stations are connected with the main indicator, and the dial of each

station has ten subdivisions, the dial D^2 should have forty subdivisions, as shown in Fig. 3, so as to totalize the records indicated by the dials of all the stations, a hand, H^2 , indicating the sum of the records.

The mechanism of the main indicator is mounted in and supported from two plates, P P' , secured to pillars P^2 , upon which the dial D is also supported, the whole being inclosed in a suitable case, which I have deemed unnecessary to show, and said mechanism is composed of a train of registering-gearing and a train of clock-gearing, operated from two independent spring-barrels, B B' , Fig. 2, respectively.

Any suitable clock mechanism may be employed, and as such mechanism is well known it will not be necessary to describe the same in detail, except in so far as regards those elements thereof which co-operate with the detector mechanism.

The main transmitting-wheel is indicated by w^2 , Fig. 2, the hour and minute hand wheels by w' w , and the transmitting-gear by w^2 , Figs. 1, 2, and 4, and b b' the squared shafts and ratchet and pawl devices for winding the springs of the barrels B B' , respectively. Of course it will be understood that the clock mechanism just described controls the movements of the hour-hand H and minute-hand H' of the detector only, the movements of the hand H^2 being controlled by the detector mechanism, which I will now describe.

The main arbor A carries the minute-hand H' and wheel w , also the hour-hand barrel S , carrying the hour-hand H and wheel w' , said barrel having at its inner end a groove, s , formed by two annular flanges, s' s ', for purposes presently explained.

Upon the barrel S is loosely mounted a barrel, S' , that carries the indicator-hand H^2 , and a ratchet-wheel, W^2 , supported from a cock, b^2 , in rear of the dial D , as shown in Figs. 1 and 2, said ratchet-wheel being held against free rotation in one direction by a spring-pawl, c^2 . The spaces between the teeth of the ratchet-wheel relatively to the spacing of the dial D^2 is such that when the wheel is rotated a distance of one tooth the hand H^2 will move from one graduation to the next succeeding one on the dial. The ratchet-wheel is controlled by and operated through the electro-magnets of all the stations in the following manner:

M is an electro-magnet in electrical communication with the electro-magnets M' of all the stations by suitable metallic connections, which I have deemed unnecessary to show, since such connections are too well known to need either illustration or description. The armature m of the electro-magnet M is connected with a lever, L^2 , upon an arbor, A^2 , by a connecting-rod, R^2 , and said arbor carries a pawl, B^2 , that is normally in engagement with one of three or more peripheral notches, e , of a disk, E . The latter is mounted on an arbor, A' , that carries a pinion, C , Figs. 2, 5, and 6, driven from the spring-bar-

rel, B' , and a gear-wheel, W' , that meshes with a pinion, I , on an arbor, A^3 . The disk E also carries on its outer face three or more pins, F , in the path of the teeth of the ratchet-wheel W^2 , and upon said disk E are also formed a like number of wedge-shaped projections, G , in the path of an angular arm, l , of a lever, L , pivoted at l' upon plate P . The opposite end 75 of the lever L is forked, as shown at l' , Fig. 4, the branches of the fork lying in the grooves, formed by the flanges s' s ' of the barrel S of the hour-hand H .

It is obvious that when the electric circuit 80 is closed at one of the stations the armature m of the electro-magnet M is attracted, and through the rod R^2 the arbor A^2 is partially rotated, thereby withdrawing the pawl B^2 from its notch e of the disk E , which pawl will immediately, on the interruption of the circuit, move back on the disk E . As soon as said pawl is disengaged from the disk the latter will be rotated by the spring-power through pinion C' until the said pawl B^2 engages with 85 the next notch. During this rotation of the disk one of the pins F will rotate the ratchet-wheel W^2 a distance equal to one tooth, and the hand H^2 from one subdivision to the next succeeding one on the dial D^2 . At the same time 95 one of the wedge-shaped projections G will move one end of the lever L on its pivot outwardly, the forked end moving inwardly against the tension of a forked spring, J , drawing the sleeve S and the hour-hand H with it, the latter being provided on its under side with a perforator, h , that perforates the strip or disk of paper d' . The forked spring J , also embracing the barrel S , acts to return the barrel into its normal position, as plainly shown in 100 Figs. 2 and 4. By this arrangement of devices a visible indication is made at each station of the number of times the electric current has been closed—that is to say, of the number of indications made by the watchman 105 at such station. A like indication is made by the main indicator of the total closures of the electric circuit at all the stations, and simultaneously therewith a permanent record thereof is made by the main recorder, that also 110 shows the precise time at which the electric circuit was closed at any one of the stations; and by locating the station-indicator below the main indicator, either in the same case or in a separate case, the precise station at which 115 the electric circuit was closed may be noted by the officer of the watch.

It is obvious that by employing a record-strip, d' , having hour and minute subdivisions corresponding with those on the clock-dial, 120 the time of each record will be permanently indicated thereon.

In order to notify the officer of the watch whenever the electric current is closed, an audible signal is given by the main indicator 125 in the manner and by the instrumentalities as follows.

As above described, the arbor A' carries a gear-wheel, W' , that meshes with a pinion, I ,

on an arbor, A^3 , that also carries an escapement-wheel, N , controlled by an escapement lever or anchor, n , pivoted upon plate P' . The arbor A^3 also carries a gear-wheel, O , and a bell-hammer, Q . The wheel O meshes with a pinion, t , on an arbor, A^4 , which latter also carries a gear-wheel, t' , that meshes with a pinion, v , on arbor V , which carries the regulating-fly W . The arbor A^5 also carries a lever, K^2 , extending upward and provided at its upper end with a flat lug, k^2 , that projects through a slot in plate P into the path of a pin, p , secured to the face of the gear-wheel t' .

As shown in Figs. 1 and 4, the lever K^2 is held by a spring, C^2 , in the end of the slot with the lug k^2 in the path of the pin p of gear-wheel t' , thus holding the entire train of detector-gearing against movement, said spring C^2 also holding the pawl B^2 in engagement with the disk E . When, however, the armature m of the electro-magnet M is attracted on the closing of the electric circuit at one of the stations, the arbor A^5 is partially rotated to disengage the pawl B^2 from the disk E , the lever K^2 being simultaneously moved toward the opposite end of the slot, with its lug k^2 out of the path of the pin p , thus permitting the spring-motor to move the train of detector-gearing, thereby causing the hammer Q to strike upon a gong, Q' , a number of blows in rapid succession controlled by the escapement, and by the time of rotation of the disk E —that is to say, by the distance traveled by the disk before its movement is again interrupted by the engagement of the pawl B^2 with one of the notches e .

As above stated, the disk has three or more notches or stops, three being shown in Figs. 1, 4, 7, and 8, and four being shown in Fig. 2. Consequently the hammer will rapidly strike the bell or gong Q' during one-third or one-fourth of a revolution of the disk E .

I do not desire to limit myself to the number of teeth on the ratchet-wheel W^2 or stop notches or pins or wedge-shaped projections on disk E , as it is evident that these may be varied without changing the function thereof.

It is obvious that should any watchman require assistance he is enabled to sound an alarm by keeping the current closed for such a length of time as to cause the hammer to strike a greater number of blows on the gong. The permanent record will then be indicated by two or more perforations in the paper d' , in proximity to each other, thereby also indicating the time at which such assistance was asked.

Having now described my invention, what I claim, and desire to secure by Letters Patent of the United States, is—

1. In a time-detector system, the combination of one or more sub-stations provided with electric indicators composed of an indicator-dial and index-hand controlled by an electro-magnet, as described, with a main station comprising an electro-magnet in electrical connection with the electro magnet or magnets of the

sub station or stations, a train of registering-gearing controlled by the electro-magnet of the main station, a time mechanism controlled by an independent power, and appliances, substantially such as described, whereby a total record of the operations of the sub-station electro magnet or magnets and a permanent record of each operation thereof, as well as a record of the time when made, is obtained, and an audible signal given at each operation of the sub-station electro magnet or magnets, for the purpose specified.

2. The herein-described electric time-detector, comprising a train of clock mechanism operated from a suitable power, a train of registering-gearing operated from an independent power and controlled by an electro-magnet, a clock and registering dial, hour and minute hands, and a registering-hand mounted upon the same arbor and operated by the clock mechanism and registering-gear, respectively, and means for displacing the hour-hand of the clock mechanism on its arbor, for the purpose specified.

3. The herein-described electric time-detector, comprising a train of clock mechanism operated from a suitable power, a train of registering-gearing operated from an independent power and controlled by an electro-magnet, a clock and registering dial, hour and minute hands, and a registering-hand mounted upon the same arbor and operated by the clock mechanism and registering-gear, respectively, and means for displacing the hour-hand of the clock mechanism on its arbor through the medium of the registering mechanism, for the purpose specified.

4. The combination, with the arbor A , hour-hand H , barrel S , and forked lever L , of the disk E , having notches e , and wedge-shaped projections G , the pawl B^2 , and means, substantially such as described, for disengaging the pawl from the disk and rotating the latter, substantially as and for the purpose specified.

5. The combination, substantially as herein set forth, of the dial D , the annular record fillet or strip d' , secured thereto, the arbor A , hour-hand H , having perforator h , the grooved barrel S of said hand and the forked lever L , with the disk E , having notches e and wedge-shaped projections G , the pawl B^2 , and means, substantially such as described, for disengaging the pawl from said disk and rotating the latter, for the purpose specified.

6. The combination, substantially as herein set forth, of the indicator-hand H^2 , the hour-hand H , its grooved barrel S , the ratchet-wheel W^2 , the arbor A , upon which said parts are mounted, and the lever L , with the disk E , having notches e , wedge-shaped projections G , and pins F , the pawl B^2 , and means, substantially such as described, for disengaging said pawl from and rotating the disk, for the purpose specified.

7. The combination, substantially as herein set forth, of the disk E , having notches e , the pawl B^2 , and lever K^2 , provided with a pro-

jection or lug, k^2 , with the spring-barrel B', bell-hammer Q, gong Q', and the described intermediate gearing, and means, substantially such as specified, for disengaging the pawl B² 5 from the disk E, for the purpose specified.

8. The combination, with the dial D, record-fillet d', secured thereto, hour-hand H, its grooved barrel S, arbor A, disk E, having notches e, and wedge-shaped projections G, 10 and the forked lever L, of the pawl B², lever K², spring-barrel B', bell-hammer Q, gong Q', and the described intermediate transmitting mechanism, and means, substantially such as specified, for disengaging the pawl from the disk, substantially as and for the purpose set forth. 15

9. The combination, with the dial D, record-fillet d' secured thereto, hour-hand H, the barrel S thereof, the hand H², ratchet W², ar-

bor A, lever L, having notches e, wedge-shaped 20 projections G, and pins F, of the pawl B², lever K², having lug k², the escapement N n, wheel t', having pin p, the hammer Q, gong Q', spring-barrel B', and transmitting-gearing connecting wheel W² with said spring-barrel, 25 and means, substantially such as described, for releasing the pawl B² from disk E, and the lug k² of lever K² from pin p of wheel t', said parts being arranged for co-operation, substantially as and for the purpose specified. 30

In testimony that I claim the foregoing I have hereunto set my hand this 27th day of February, 1883.

ANATOLE LASMOLES.
